HATCH CONSTRUCTION

Paul E. Finger, New Kensington, Pa., assignor to
 P. H. Murphy Company, New Kensington, Pa.,
 a corporation of Pennsylvania

Application April 11, 1936, Serial No. 73,954

16 Claims.

(Cl. 108—5)

This invention relates to the hatch construction of a car roof. It has for its principal objects to produce a strong, durable, simple and economical weatherproof hatch construction and to obtain other advantages hereinafter appearing. The invention consists in the hatch construction and in the combinations and arrangements of parts hereinafter described and claimed.

In the accompanying drawings, which form part of this specification and wherein like symbols refer to like parts wherever they occur,

Fig. 1 is a plan view of the end portion of a car roof embodying my invention,

Fig. 2 is a partial transverse section through the roof on the line 2—2 in Fig. 1,

Fig. 3 is a vertical partial longitudinal section through the roof on the line 3—3 in Fig. 1,

Fig. 4 is an enlarged fragmentary section similar to Fig. 2 through one side of the hatchway,

Fig. 5 is an enlarged fragmentary section similar to Fig. 3 through one side of the hatchway,

Figs. 6 and 7 are views similar to Figs. 4 and 5, respectively, illustrating a modified form of hatch construction,

Figs. 8, 9 and 10 are views similar to Fig. 7 illustrating other modified forms of hatch construction,

Fig. 11 is a fragmentary section similar to Fig. 2 illustrating another modified form of hatch construction,

Fig. 12 is a vertical section on the line 12—12 in Fig. 11,

Fig. 13 is an enlarged fragmentary section similar to Fig. 11,

Fig. 14 is a plan view of the metal hatch frame shown in Figs. 11, 12 and 13; and

Fig. 15 is a side view of the metal hatch frame shown in Fig. 14.

In Figs. 1 to 5 of the accompanying drawings, my invention is shown in connection with a metal refrigerator car roof comprising end and intermediate roof sheets 1 and 2, respectively, that extend from side plate 3 to side plate 3 of the car with their eaves ends resting on and riveted or otherwise rigidly secured to the outstanding top flanges of eaves angles 4, whose depending flanges are riveted or otherwise rigidly secured to the upstanding inner side flanges of said side plates. The end and intermediate roof sheets are provided along their adjacent margins with upstanding flanges 5 that are straddled by a seam cap 6 that is riveted or otherwise secured to said flanges and to the top flanges of the eaves angles 4. At the end of the car, the end roof sheet 1 is supported on and riveted or otherwise rigidly secured to the outstanding top flange of an end angle 7, whose depending flange is riveted or otherwise rigidly secured to the upstanding flange of a metal end plate 8.

The roof is provided with one or two hatch-

ways that lead downwardly through the end sheet 1 and a framework located therebelow into the interior of the car. Said framework comprises spaced parallel frame or carline members 9 that extend from side plate to side plate of the car with their ends rigidly secured thereto by suitable brackets 10. As shown in Figs. 3 and 5, these carline members comprise oblique metal angles disposed with one flange extending laterally outwardly from the other flange and said other flange inclining downwardly and inwardly.

Each hatchway opening is provided with a metal frame A comprising a hopper member or portion 11, which fits between the spaced carline members 9, and a hollow upper end rim portion or member 12 of substantially inverted channel-shaped section located above the general level of the roof and supported on tops of said carline members. The hopper member or portion 11 of the metal hatch frame A has its sides converging downwardly to rest flatwise against the downwardly converging side flanges of the carline members 9 and to constitute a seat for a hatch plug (not shown) and is provided at its top with an outstanding flange 13; and the rim portion or member 12 of said hatch frame is of substantially Z-shaped section and is arranged with its top flange 14 extending inwardly to constitute a support for the outstanding flange 13 of said hopper member. The top flange 13 of the hopper member 11 is rigidly secured to the top flange 14 of the rim member by means of a weld 15 of added metal which extends continuously along the outer edge of the hopper flange.

The outstanding bottom or base flange 16 of the Z-shaped rim member or portion 12 of the hatch frame is supported on the two carline members 9 with its edges flush with the edges of the top flanges of said carline members; and said hatch frame is rigidly secured to said carline members preferably by means of a weld 17 of added metal that extends along the flush edges of said flanges and by means of welds 18 of added metal that extend along the lower edges of the depending side flanges of said carline members and the sides of the hopper portion or member 11 that fits therebetween. The end roof sheet has an upwardly offset portion or boss 19 that has a flangeless opening 20 cut therein of larger size than the hollow rim portion or member 12 of the hatch frame. The portion of the roof sheet boss 19 that surrounds the hatch opening 20 therein overlaps and is supported on the outstanding base flange 16 of the rim member 12 of the hatch frame; and said end or hatch sheet is secured to said base flange by means of a weld 21 of added metal that extends continuously along the edge of the hatch opening 20 in said sheet.

The construction illustrated in Figs. 6 and 7 is similar to the construction hereinbefore described

except that the hopper and rim portions of the metal hatch frame are integral.

In the modification shown in Fig. 8 the rim member of the metal hatch frame comprises a channel 12a whose bottom or hatch sheet supporting flange 18a rests upon a wooden carline member 9a. The hopper member 11a of this hatch frame forms a metal lining for a wooden hatch frame B and covers and protects the top thereof.

In the modified hatch construction shown in Fig. 9, the rim member 12b of the metal hatch frame is of Z-shaped section and surrounds the upper end of a wooden hatch frame B' with its upper flange 14b extending inwardly over the upper edge thereof and with its bottom or hatch sheet supporting flange 16b resting on the wooden carline 9b. The hopper member 11b of the hatch frame is disposed within the wooden hatch frame B' and has an outstanding top flange 13b that extends beneath the top flange 14b of the rim member 12b and overlaps the upper edge of said wooden hatch frame.

The construction shown in Fig. 10 is similar to that shown in Fig. 9 except that the rim and hopper portions of the metal hatch frame are made integral.

In the modified hatch construction shown in Figs. 11 to 15, inclusive, the metal hatch frame comprises a bossed up portion, a hollow upstanding boss 23 surrounded by a flat marginal portion 24 and having a hatch opening cut in its top that communicates with the upper end of a hopper member 11c located in a wooden hatch frame B'' that extends upwardly into and is covered by said boss. The base or marginal portion 24 of the bossed-up hatch frame rests upon the top of wooden carline members 9c and is provided with depending side flanges 25 that overhang the remote side faces of said carline members and are rigidly secured flatwise thereto by means of lag screws or other fastening members 26. In this construction, like the constructions previously described, the hatch sheet is provided with an opening that surrounds the bossed-up portion of the hatch frame and is secured to the base flange of the latter by means of a weld that extends continuously around the edge of said opening.

The hatch construction hereinbefore described has numerous advantages. The metal hatch frame is reinforced and stiffened above the level of the roof by means of a hollow rim portion or boss and forms a rigid cross-connection between the carline members. The metal carline members cooperate with the hollow rim portion of the metal hatch frame to form strong hollow box girder sections along two sides thereof. The flangeless opening in the hatch sheet is made large enough to accommodate misalignment of said opening and the metal hatch frame. The weld along the edge of the opening in the hatch sheet forms a rigid weatherproof connection between the lapped portions of the hatch sheet and the base flange of the rim portion of the metal hatch frame; and the location of the hatch sheet above said flange permits removal and replacement of said sheet without disturbing said hatch frame.

What I claim is:

70. 1. A hatch construction for car roofs comprising a roof sheet provided with a hatch opening located entirely in a plane parallel to the body of said sheet, a metal hatch frame located in said hatch opening and having an outstanding marginal flange that extends beneath said roof

sheet around the margin of the hatch opening therein, and a weld of added metal extending continuously along the edge of said opening for securing said edge to the top of the flange of said hatch frame.

2. A hatch construction for car roofs comprising a roof sheet provided with a hatch opening and a metal hatch frame having a hopper portion located in said opening and a depending rim portion terminating at its lower end in an outstanding flange that extends beneath said roof sheet around the margin of the hatch opening therein.

3. A hatch construction for car roofs comprising a roof sheet provided with a hatch opening, a metal hatch frame having a hopper portion located in said opening and provided at its upper end with a downwardly opening rim portion terminating at its lower end in an outstanding flange that extends beneath said sheet around the margin of the hatch opening therein, and a weld of added metal extending along the edge of said hatch opening for securing said sheet to the top of said flange.

4. A hatch construction for car roofs comprising a roof sheet provided with a hatch opening, and a metal hatch frame having a hopper portion located in said opening with its upper portion located above said roof sheet and provided with a hollow rim having a flange that extends outwardly therefrom beneath said sheet around the margin of the hatch opening therein, said sheet being welded to said flange around the edge of said hatch opening.

5. A hatch construction for car roofs comprising a roof sheet having a hatch opening therein, and a metal hatch frame comprising a hopper member mounted in said hatch opening and provided above said roof sheet of the roof with a lateral flange and a rim member surrounding the upper portion of said hopper member and provided at its top with a lateral flange arranged in lapped relation with and secured to the lateral flange of said hopper member, said rim member being provided at its bottom with a lateral flange arranged in lapped relation with and secured to 45 said roof sheet around the hatch opening therein.

6. A hatch construction for car roofs comprising a roof sheet having a hatch opening therein, and a metal hatch frame comprising a hopper member mounted in said opening and provided above said roof sheet with an outstanding flange and a rim member surrounding said hopper member above said roof sheet and provided with an inwardly extending upper flange arranged in lapped relation with the flange of said hopper member, said rim member being provided with a lower outstanding flange arranged in lapped relation with the roof sheet around the hatch opening therein.

7. A hatch construction for a car roof comprising a roof sheet having a hatch opening therein, a metal hatch frame located in said opening comprising a hopper member extending above said roof sheet and a rim member surrounding and secured to said hopper member above said roof sheet and provided with an outstanding base flange that extends beneath said roof sheet around the hatch opening therein, and a weld of added metal extended continuously along the edge of said hatch opening for securing 70 said roof sheet to said flange.

8. A hatch construction for a car roof comprising a roof sheet having a hatch opening therein, a metal hatch frame comprising a hopper member mounted in said opening and pro- 75

- vided above said roof sheet with an outstanding top flange, a rim member surrounding the upper portion of said hopper member and provided with a top flange that extends inwardly beneath 5 the top flange of said hopper member, a weld securing the edge of the hopper flange to the rim flange, said rim member having a bottom flange that extends beneath said roof sheet around the hatch opening therein, and a weld securing 10 said sheet to said bottom flange along the edge of said hatch opening therein.
9. A hatch construction for car roofs comprising a roof sheet having a hatch opening therein, a metal hatch frame comprising a hopper member 15 extending above said roof sheet and provided at its top with an outstanding flange, a rim member surrounding the upper portion of said hopper member and provided at its top with a flange and is overlapped by the top flange of said 20 hopper member, a weld of added metal extending along the edge of the top flange of said hopper member for securing it to the top flange of said rim member, said rim member being provided with an outstanding base flange overlapped by 25 the portion of the roof sheet surrounding the hatch opening therein, and a weld of added metal extending along the edge of said hatch opening for securing said roof sheet to the base flange of said rim member.
- 30 10. A hatch construction for car roofs comprising a roof sheet having a hatch opening therein, frame members located beneath said roof sheet and extending across the hatch opening therein, and a metal hatch frame having a hopper portion 35 extending downwardly through said hatch opening between the spaced frame members therebelow and having a hollow rim portion extending above the general level of the roof and provided at the lower edge of its outer side wall 40 with an outstanding base flange that rests upon the tops of said frame members and extends beneath said roof sheet around the hatch opening therein.
11. A hatch construction for car roofs comprising a roof sheet provided with a hatch opening located entirely in a plane parallel to the body of said sheet, metal frame members located beneath said roof sheet and extending across the hatch opening therein, a metal hatch frame having a hopper portion 45 extending downwardly through said hatch opening between the spaced frame members therebelow and having a hollow rim portion extending above the general level of the roof and provided at the lower edge of its outer side wall 50 with an outstanding base flange that rests upon the tops of said frame members and extends beneath said roof sheet around the hatch opening therein, welds extending along the lower edges of said frame members for securing 55 the hopper portion of said hatch frame thereto, a weld extending along the edge of said base flange for securing the same to said frame members, and a weld extending around the hatch opening in said sheet for securing the latter to 60 said base flange.
12. A hatch construction for car roofs comprising a roof sheet having a hatch opening therein, metal frame members located beneath said roof sheet and extending across the hatch 65 opening therein, a metal hatch frame having a hopper portion extending downwardly through said hatch opening between the spaced frame members therebelow and having a hollow downwardly opening rim portion surrounding the up- 70 per portion of said hopper portion above the general level of the roof and provided at the lower edge of its outer side wall with an outstanding base flange that rests upon the tops of said frame members and extends beneath the portion of the roof sheet around the hatch opening therein, and means for rigidly securing said hatch frame to said frame members, whereby said frame members cooperate with the hollow downwardly opening rim portion of said hatch frame to form hollow box girders above said frame members.
13. A hatch construction for a car roof comprising a roof sheet having a hatch opening therein located entirely in a plane parallel to the body of said sheet, and a metal hatch frame comprising a plate having a hollow upstanding boss formed therein that extends through said opening above the general level of the roof and is provided at its top with a hatch opening, said plate having its marginal portion located beneath the portion of the roof sheet that surrounds the hatch opening therein.
14. A hatch construction for a car roof comprising a roof sheet having a hatch opening therein located entirely in a plane parallel to the body of said sheet, a metal hatch frame comprising a plate having a hollow upstanding boss formed therein that extends through said opening above the general level of the roof and is provided at its top with a hatch opening, said plate having its marginal portion located beneath the portion of the roof sheet that surrounds the hatch opening therein, and spaced frame members located beneath said roof sheet and supporting the marginal portion of said bossed plate.
15. A hatch construction for a car roof comprising a roof sheet having a hatch opening therein located entirely in the plane of the body of said sheet, a metal hatch frame comprising a plate having a hollow upstanding boss formed therein that extends through said opening above the general level of the roof and is provided at its top with a hatch opening, said plate having its marginal portion located beneath the portion of the roof sheet that surrounds the hatch opening therein, spaced frame members located beneath said roof sheet and supporting the marginal portion of said bossed plate, the marginal portion of said plate being provided with depending flanges that overlap and are rigidly secured to the remote side faces of said frame members.
16. A hatch construction for a car roof comprising a roof sheet having a hatch opening therein located entirely in the plane of the body of said sheet, a metal hatch frame comprising a plate having a hollow upstanding boss formed therein that extends through said opening above the general level of the roof and is provided at its top with a hatch opening, said plate having its marginal portion located beneath the portion of the roof sheet that surrounds the hatch opening therein, spaced frame members located beneath said roof sheet and supporting the marginal portion of said bossed plate, the marginal portion of said plate being provided with depending flanges that overlap and are rigidly secured to the remote side faces of said frame members, and welds for securing said sheet to the marginal portion of said plate around the hatch opening in said sheet and for securing said marginal portion to said frame members.
